UNITED STATES PATENT OFFICE.

FRANCIS F. HAMILTON, OF INDIANAPOLIS, INDIANA.

DESIGN FOR A BOX.

Application filed January 7, 1924. Serial No. 8,259. Term of patent 14 years.

To all whom it may concern:

Be it known that I, FRANCIS F. HAMILTON, a citizen of the United States, residing at Indianapolis, in the county of Marion and State of Indiana, have invented a new, original, and ornamental Design for a Box, of which the following is a specification, reference being had to the accompanying drawing, forming a part thereof.

The single figure of the drawing is a perspective view of a box embodying my new design, there being a metallic handle attached to each end formed to curve slightly downward, and the box having a cedar finish.

I claim:

The ornamental design for a box, as shown and described.

FRANCIS F. HAMILTON.
